UNITED STATES PATENT OFFICE

142,949

DESIGN FOR A COMBINED DOOR CHECK AND DEODORANT DIFFUSER

Israel Dobkin, Pittsburgh, Pa.

Application June 19, 1945, Serial No. 120,203

Term of patent 14 years

(Cl. D16—2)

To all whom it may concern:

Be it known that I, Israel Dobkin, a citizen of the United States, residing in Pittsburgh, in the county of Allegheny and State of Pennsylvania, have invented a new, original, and ornamental Design for Combined Door Check and Deodorant Diffuser, of which the following is a specification, reference being had to the accompanying drawing, forming part thereof.

I claim:

The ornamental design for a combined door check and deodorant diffuser, as shown.

ISRAEL DOBKIN.
